FLUORESCENT LIGHTING FIXTURE

Edwin D. Tillson, William E. Janness, and Donald W. Davis, Highland Park, Ill.

Application February 13, 1956, Serial No. 40,117

Term of patent 14 years

(CL. D48—23)

Fig. 1 is a bottom perspective view of a fluorescent lighting fixture, showing our new design; and

Fig. 2 is a fragmentary enlarged view showing a portion of a plastic diffusing member as shown in Fig. 1.

We claim:

The ornamental design for a fluorescent lighting fixture, as shown.
